UNITED STATES PATENT OFFICE

HUBERT KRESS, OF ERLANGEN, GERMANY

X-RAY APPARATUS

Application filed November 7, 1927, Serial No. 231,487, and in Germany December 8, 1926.

This invention relates to improvements in X-ray apparatus and has particular reference to a protective mounting for the X-ray tube.

5 An object of the invention is to provide an apparatus involving an improved mounting for an X-ray tube which will prevent persons in close proximity to the apparatus from coming in direct contact with any parts thereof through which is passed the high potential current utilized in the operation of the tube.

10 Another object is to support the X-ray tube in a manner which will permit of its being adjusted to various positions relative to the object to be treated in order to secure the most efficient results in the operation of the apparatus.

15 A further object is to control the emission of the rays from the tube by means of a shutter which is adjustable relative to an apertured tube-enclosing casing so that the rays may be entirely shut off or the direction thereof controlled at the will of the operator.

20 The above and other objects will appear more clearly from the following detail description, when taken in connection with the accompanying drawings, which illustrate preferred embodiments of the inventive idea.

25 In the drawings—

Figure 1 is a partial vertical longitudinal section of one form of the apparatus constructed in accordance with the invention;

Figure 2 is a similar view of another form;

30 Figure 3 is a similar view of still another form;

Figure 4 is a longitudinal section through that portion of the apparatus adjacent the X-ray tube;

35 Figure 5 is a similar view taken in a plane at right angles to Figure 4; and

Figure 6 is a section on the line 6—6 of Figure 1.

40 In accordance with the present invention it is proposed to enclose the high potential circuit and the X-ray tube within a grounded protective sheath which will adequately protect the elements and prevent contact therewith by persons adjacent the apparatus.

45 Figure 1 illustrates an adaptation of the ap-

paratus which is capable of being suspended from a ceiling or other overhead support and in this embodiment *a* represents a housing which is secured to the ceiling of a room and which may be made of porcelain or other similar material so as to contain the transformer (not shown) utilized to supply high potential current to the X-ray tube *c* at the lower end of the apparatus. A universal joint connection *b* is utilized to join a metal tube *d* with the transformer housing and from said tube is supported the remainder 55 of the apparatus. This universal joint permits of movements of the X-ray tube in various directions. An insulating tube *e* is secured to and surrounds the inner tube *d* and has rigidly affixed to the exterior thereof a metallic grounded casing *f*, the lower portion 60 of which encloses the X-ray tube *c*. The upper portion of the casing *f* directly below the universal joint *b* supports a protective bowl-shaped housing *s* which may be of wicker-work or the like and which is utilized as an additional protective means for the apparatus. 65

70 One of the electrodes of the tube *c* is connected in a known manner to ground. For the purpose of cooling the anti-cathode, the tube *c* may be provided with a solid stem *g* made of a material which will absorb the heat radiated by the anti-cathode and said stem extends vertically upward into the tube *d* and forms one of the terminals for the high potential current. To permit of sufficient air circulation to at least partially conduct the heat from the interior of the apparatus, the casing *f* is provided with openings at its lower end, as will presently appear. Air enters these openings and passes around the tube *c* and thence into the tube *e*. The guide rings *w* have openings *x* therein for permitting the air to then pass upwardly between the tubes *d* and *e* and then out through openings *y* in the upper ring of the housing *s*. 75

80 Instead of suspending the apparatus from the ceiling as just described, it may be attached to a wall as shown in Figure 2, in which instance the housing *a* enclosing the transformer is secured to said wall and has 85 projecting therefrom the extensible arm *q* 90

95 Figure 1 illustrates an adaptation of the apparatus which is capable of being suspended from a ceiling or other overhead support and in this embodiment *a* represents a housing which is secured to the ceiling of a room and which may be made of porcelain or other similar material so as to contain the transformer (not shown) utilized to supply high potential current to the X-ray tube *c* at the lower end of the apparatus. A universal joint connection *b* is utilized to join a metal tube *d* with the transformer housing and from said tube is supported the remainder 100

enclosing the high potential conductors and said arm terminates in one portion of a spherical or universal joint *b*, the other portion of which carries the tube *d*. The outer 5 insulating tube *e* may be slidable upon the tube *d* in order to permit of vertical adjustments of the lower portion of the apparatus carrying the X-ray tube *c*. For this purpose the construction is the same as in Figure 10 1, wherein the rings on the tube *d* act as guides for the tube *e* when it is adjusted. The anti-cathode of the tube *c* may also be provided, as shown in Figure 2, with a surface cooler, conventionally illustrated at *h*, which 15 cooler is spaced from the inner wall of the tube enclosing the same to permit of circulation of air through the tube.

As shown in Figure 3, it is possible to provide an apparatus which is neither attached 20 to the ceiling or wall, but which constitutes a stand the base of which comprises a housing *i* for enclosing the transformer and a standard *j* vertically adjustable relative to the base. Rotatably supported by the stand- 25 ard *j* is a horizontal arm consisting of the sections *k*, the outer of which is adjustable relative to the inner section and which carries a bearing *l* in which the insulating tube *e* is rotatably supported. From this construction 30 it will be apparent that adjustments of the tube *c* may be made about the vertical axis of the standard *j* and also of the tube *e*.

The outer extremity of the casing *f* adjacent the tube *c* therein is rounded and provided with an elongated aperture *r* through 35 which the rays from the tube *c* may pass. In order to control the emission of these rays from the casing *f* the same is provided at its outer end and in spaced relation thereto with a guide *m* extending on both sides of the 40 casing and around its outer end. Slidable in this guide is a flexible shutter *o* made of a material which is impervious to the X-rays and which is provided therein intermediate 45 its ends with an opening *n* which can be brought into registration or alignment with the aperture *r* by a movement of the shutter in its guide so as to permit of the projection of the rays from the interior of the casing 50 and in any desired direction within the range of the ends of the aperture *r*. On the other hand, the shutter *o* may be adjusted to a position where the opening *n* will not be in alignment with any portion of the opening *r* thus 55 preventing any emission of the rays from the casing. The casing *f* is formed with an extension *t* upon which is rotatably supported one end of an arm *u*, the other end of which carries a compression cone *p* through which 60 the X-rays pass from the opening *n* in the shutter. This compression cone *p* is connected at all times to the shutter by a link *v* so that when the cone is swung about the extension *t* as an axis the shutter *o* will move in 65 unison with said cone so that the latter will

always be in alignment with the opening *n* in the shutter.

By spacing the guide *m* from the casing *f* the free circulation of air through the latter, previously referred to, is not hindered as the 70 air may then pass through the aperture *r* and between the casing and guide.

What is claimed is:

In an X-ray apparatus, a casing in which 75 an X-ray tube is mounted, said casing having an aperture through which the rays pass, a flexible shutter movable relative to the casing to cover and uncover the aperture therein, a guide for said shutter in which the same is slidably mounted, a compression cone 80 through which the rays also pass supported by said casing in front of the aperture therein, and a connection between said compression cone and shutter for moving the same in unison.

HUBERT KRESS.
